L. Q. C. Wishart, of Philadelphia, Pa.
Letters Patent No. 1161. Dated Oct. 25-1859.

The schedule referred to in these Letters Patent and making part of the same.

To all whom it may concern:

Be it known that I, L. Q. C. Wishart, of Philadelphia, in the County of Philadelphia and State of Pennsylvania, have produced a new and useful ornamental design for Pine Tree Tar Cordial Bottles, and I do hereby declare that the following is a full, clear and exact description of the same,

In the drawing.

Fig. 1. represents a side view of a bottle having square sides and square corners; the side represented having a pine-tree blosom or moulded on it so as to be slightly in relief, or elevated.

Fig. 2. is a similar view of another side of the bottle with L. Q. C. WISHART'S. blown or moulded on it in raised letters.

Fig. 3. is a similar view showing another side of the bottle having PINE-TREE TAR CORDIAL, PHIL. blown or moulded on it, in raised letters.

Having thus described my design, what I claim and desire to secure by Letters Patent, is

The ornamental design, described, and represented in the drawing, for Pine Tree Tar Cordial bottles.
